[57] CLAIM

We claim the ornamental design for a cooler, as shown and described.

DESCRIPTION

FIG. 1 is a top front right side perspective view of a cooler showing our new design;

FIG. 2 is a right side elevational view thereof;

FIG. 3 is a left side elevational view thereof;

FIG. 4 is a front elevational view thereof;

FIG. 5 is a top plan view thereof;

FIG. 6 is a right side perspective view of another embodiment of the present invention, the only difference being the curved glass panel within the door; and,

FIG. 7 is a front elevational view of the embodiment of FIG. 6 (the other views are similar to FIGS. 2, 3, and 5).

The broken lines in all views are for illustrative purposes only and form no part of the claimed design.
